United States Patent Office

Des. 176,317

Patented Dec. 13, 1955

176,317

PACKING CONTAINER

Harold Fox, Minneapolis, Minn.

Application September 7, 1954, Serial No. 32,167

Term of patent 3½ years

(Cl. D58—12)

Fig. 2

Fig. 4

Fig. 3

Fig. 1 is a perspective view of a packing container showing my new design;

Fig. 2 is a view in top plan;

Fig. 3 is a view in side elevation; and

Fig. 4 is a view in end elevation, as seen from the left to the right with respect to Fig. 3.

The side of my packing container opposite to that shown in Figures 1 and 3 is identical to the side shown.

I claim:

The ornamental design for a packing container, as shown and described.
